UNITED STATES PATENT OFFICE.

BERNARD G. VAUGHAN, OF JOLIET, ILLINOIS, ASSIGNOR TO NATIONAL MATCH COMPANY, OF JOLIET, ILLINOIS, A CORPORATION OF ILLINOIS.

MATCH-MAKING MACHINE.

Application filed July 26, 1922. Serial No. 573,198.

To all whom it may concern:

Be it known that I, BERNARD G. VAUGHAN, a citizen of the United States, residing at Joliet, Illinois, have invented a certain new and useful Improvement in Match-Making Machines, of which the following is a full, clear, and exact description, such as will enable others skilled in the art to which it appertains to make and use the same.

10 This invention relates to match making machines of the type that comprise a vertically-disposed hopper filled with match splints, and a reciprocating setting head arranged at the lower end of the hopper for removing splints from same and inserting the splints in an endless carrier that moves the splints through tanks containing substances that are used to treat the splints and form the heads of the matches.

15 Prior to my invention it was the usual practice, in manufacturing matches in match making machines of the general type above described, to feed the match splints from a source of supply to a machine where-

20 in the match splints were arranged in an orderly manner and introduced into receptacles which were thereafter carried by a workman from the filling machine to the match making machine and dumped manually into the hopper of the match making machine. This method of handling match splints requires the services of several operatives for carrying the match splint receptacles from the filling machine to the match making machine, it requires the services of operatives who are careful and conscientious in order to insure an adequate supply of match splints to the match making machine, and even when careful operatives are em- 25 ployed, there is considerable waste of match splints, due to the splints spilling out of the receptacles when they are being carried from the filling machine to the match making machine and when they are being dumped into the hopper of the latter.

30 The main object of my invention is to provide a match making machine which comprises as an integral part thereof an apparatus of novel construction for arranging match splints in an orderly manner and feeding the splints directly into the hopper from which the setting head of the machine removes the splints and inserts them in the endless match splint carrier.

35 Another object is to provide a novel mecha-

nism for feeding match splints to the hopper of a match making machine and for automatically cutting off the supply of splints to the hopper when said hopper becomes full.

40 And still another object is to provide a match making machine having the characteristics above referred to that is of simple construction, reliable in operation and of such design that improperly arranged match splints will be automatically discharged 45 from the splint feeding mechanism before they reach the hopper of the machine.

46 Figure 1 of the drawings is a side elevational view, partly broken away, of the 50 match splint feeding mechanism of a match making machine constructed in accordance with my invention.

55 Figure 2 is an end elevational view of said mechanism.

60 Figure 3 is a top plan view of a portion of the match splint hopper and the trough through which the match splints move while being fed into the hopper.

65 Figure 4 is a side elevational view of the 60 parts shown in Figure 3: and

70 Figures 5 and 6 are detail views of the clutch that is used for rendering the match splint distributing member inoperative when the hopper of the machine becomes 75 filled, Figure 5 being a sectional view taken on the line 5-5 of Figure 6, and Figure 6 being a longitudinal sectional view through the co-operating members of the clutch.

76 Referring to the drawings which illustrate the preferred form of my invention, A designates the vertically-disposed hopper of a match making machine of the type that is provided with a reciprocating setting head (not shown) for receiving the splints from the lower end of the hopper A and inserting the splints in an endless carrier (not shown) that dips the splints in the solutions that are used to treat the splints and form the heads of the matches.

80 My improved match making machine comprises a match splint distributing member B which preferably consists of a horizontally-disposed, rotatable screen provided at one end with an opening into which the 85 match splints are discharged into the interior of same from a chute C that leads from a suitable source of supply of match splints, said distributing member B being rotatably mounted in a housing B' which is provided 90

at its lower end with a discharge opening B² arranged above a number of downwardly-inclined chutes D that lead to a horizontally-disposed trough E through which the match splints are fed to the upper end of the hopper A of the machine. The trough E is arranged at right angles to the chutes D and a feeding device F is provided for feeding the match splints through the trough E into the upper end of the hopper A. In the form of my invention herein illustrated the match splint feeding device F consists of an endless sprocket chain extending around sprocket wheels 1 and 2 and over guides 3 on the trough E and provided with teeth or fingers 4 that project downwardly into the trough E so as to move the match splints longitudinally through said trough into the hopper A of the machine when the chain F is traveling in the direction indicated by the arrows α in Figure 1. The sprocket wheel 2 is an idler and the sprocket wheel 1 is connected to a horizontally-disposed shaft 1^a that is driven by a belt 5 which passes around a drive pulley on a shaft 6 that is driven from any suitable source of power, as for, example, by a drive belt 7, as shown in Figure 1.

The fingers 4 of the splint feeding device extend transversely of the trough E and virtually form partitions in said trough that divide the interior of same into a number of compartments, each of which holds a certain approximate number of match splints, which compartments travel longitudinally of the trough E and discharge the match splints onto a vibrating member G at the left hand end of the trough E that feeds the splints towards the discharge opening in the left hand end of the trough E that is arranged above the hopper A of the machine. The match splints pass through the meshes of the screen B downwardly into the chutes D and travel through said chutes endwise, and as the trough E is arranged at right angles to the chutes D, the splints will lie transversely of the trough E parallel to the fingers 4 of the feeding device F. In order to insure the splints being arranged in an orderly manner, in parallel relation to each other, and in parallel relation to the fingers 4 of the splint feeding device, means is provided for reciprocating the trough E endwise while the splints are being fed through said trough. In the form of my invention herein illustrated the means just referred to consists of a vertically-disposed shaft 8 rotatably mounted in a stationary bearing 9 and provided at its upper end with an eccentrically-disposed pin 10 that projects into a hole in a member 11 on the underside of the trough E, the rotary movement of said shaft 8 causing the trough E to be reciprocated endwise in stationary guides E' in which it slides.

The shaft 8 can be driven by any suitable means, such, for example, as a beveled pinion on the lower end of same that meshes with a beveled pinion 13 on a horizontally-disposed shaft 14 provided with a worm 15 that meshes with a worm gear 16 secured to the drive shaft 6.

The trough E is provided at its left hand end with a vibrating member G, previously referred to, that preferably consists of a downwardly-inclined bar provided in its upper edge with notches or teeth 17 which tend to feed the splints forwardly towards the hopper A of the machine, the member G being combined with the trough E in such a manner that it can rock vertically slightly relatively to said trough. Any suitable means can be used for vibrating the feeding member G, but I prefer to pivotally connect the right hand end of said member to the trough by means of a projection 18 on said member that passes through an eye 19 on the bottom of the trough, as shown in Figure 4, and connect the left hand end of said member G with a vibrating means that rocks said member when the splint feeding device F is in operation, the vibrating means herein illustrated consisting of a horizontally-disposed shaft 20 mounted in stationary members 21 of the frame of the machine and provided with a disk 22 that is equipped with a laterally-projecting, eccentrically-disposed pin 24 that fits in a bearing 25 on the underside of the member G, as shown in Figure 4, a portion of the bottom of the trough E being broken away in Figure 3 so as to show the disk 22. The shaft 20 is driven by a belt 26 that passes around a pulley combined with the sprocket wheel 1 of the splint feeding device F, so as to cause the free end of the member G to move upwardly and downwardly when the splint feeding device F is in operation. In view of the fact that the member G is carried by the reciprocating trough E, said member G exerts pressure on the match splints in a direction to push them upwardly and forwardly towards the discharge opening in the left hand end of the trough E through which the match splints fall into the hopper A. The trough E is provided at opposite sides of the member G with openings 27, as shown in Figure 3, which are so arranged that improperly arranged splints will drop through said openings into a suction conduit 28 having a funnel-shaped portion that is arranged underneath the notched feeding member G. Accordingly, any match splints being fed through the trough E that are not arranged transversely of said trough in parallel relation to the fingers 4 of the feeding device F will escape through the openings 27 in the trough into the suction conduit 28, thereby preventing improperly positioned splints

from being discharged into the hopper A of the machine. In order to insure the ends of the feeding fingers 4 bearing snugly against the bottom of the trough E, said trough is provided with a false bottom formed by a resilient strip 29 that has sufficient tension to insure the ends of the fingers 4 bearing against same when said fingers are traveling longitudinally through the trough E. 60

10. The splint distributing screen or member B is rotated by a sprocket chain or other suitable means 30 that is driven from the horizontally-disposed shaft 14, and in order that said distributing member will be cut 15 out of service automatically when the hopper A becomes filled with match splints, a clutch is provided for disconnecting the chain 30 from the shaft 14 under certain conditions. One convenient way of stopping 20 the splint distributing member B when the hopper A becomes full is to arrange a pivotally mounted governing member 31 at the left hand end of the trough C in such a way that said member will close an electric circuit 32 and thus energize a solenoid 33 that trips said clutch when the hopper A becomes filled with match splints, and the adjacent portion of the trough E becomes filled with match splints to such an extent that said splints exert pressure on the right hand end of the governing member 31, and thus rock said member in a direction to close the circuit 32 which it controls, the governing member 31 being so arranged that it normally floats upon the supply of splints in the hopper. The clutch previously referred to may consist of two co-operating clutch members 34 and 34^a, and a tripping device 35 connected to the core of the solenoid 33 in such a way that when said solenoid is energized, the tripping device 35 will be moved upwardly, thereby causing the clutch members 34 and 34^a to be disengaged, whereupon the splint distributing member B will cease to rotate. When the distributing member B is at rest the supply of splints to the chutes D will be cut off, but the continued operation of the setting head of the machine causes 50 splints to be removed from the lower end of the hopper A, thereby reducing the quantity of splints in the left hand portion of the trough E, and consequently, permitting the governing member 31 to rock in a direction to open the circuit 32 and cause the core of the solenoid 33 to move in a direction to restore the clutch tripping device 35 to its normal inoperative position, whereupon the clutch members 34 and 34^a will be re-engaged so as to resume the feeding of the match splints to the trough E. 60

The reciprocating movement that is imparted to the trough E is very slight, only enough to agitate the splints sufficiently to straighten them out or arrange them in

parallel relation to each other, and the left hand portion of said trough in which the discharge opening is formed is preferably mounted directly upon the upper end of the hopper A, so as to insure the discharge 70 portion of the trough remaining in operative relationship with the upper end of the hopper A. While I have herein illustrated and described the splint feeding device as consisting of an endless chain provided with fingers that travel through the trough E, and have illustrated the particular means which I am now using in my commercial machine for reciprocating the trough, for actuating the feeding member G in the discharge portion of said trough and for rendering the splint distributing member B inoperative when the hopper A of the machine becomes filled with match splints, I wish it to be understood that it is immaterial, so far as my broad idea is concerned, what particular means is employed for feeding the match splints into the hopper A of the machine and for tripping the clutch and arranging the splints in an 80 orderly manner before they are introduced into said hopper. 85

Having thus described my invention, what I claim as new and desire to secure by Letters Patent is:

95 1. A match making machine, comprising a hopper adapted to hold match splints that are removed from the hopper and inserted in the match splint carrier of the machine, a match splint feeding mechanism for introducing match splints directly into said hopper, a distributing member adapted to receive match splints from a source of supply and deliver them to said feeding mechanism, and means for automatically rendering said distributing member inoperative under certain conditions so as to interrupt the delivery of the splints to said feeding mechanism. 100

105 2. A match making machine, comprising a hopper adapted to hold match splints that are removed from the hopper and inserted in the match splint carrier of the machine, mechanism for arranging match splints in an orderly manner and feeding them directly into said hopper, a distributing member adapted to receive match splints from a source of supply and deliver them to said feeding mechanism, and means for causing said distributing member to come to rest automatically so as to cut off the supply of splints to said feeding mechanism after the hopper has become filled comprising a governing member that normally floats upon the splints in the hopper. 110

115 3. A match making machine, comprising a hopper adapted to hold match splints that are removed from the hopper and inserted in the match splint carrier of the machine, a mechanism for feeding match splints di- 120

rectly into said hopper, means for supplying match splints to said mechanism, and means for automatically cutting off the supply of splints to said feeding mechanism when the supply of splints in said hopper exceeds a certain amount and for resuming the supply of splints to said feeding mechanism when the supply of splints in said hopper has been diminished to normal.

4. A match making machine, comprising a hopper adapted to hold match splints that are removed from the hopper and inserted in the match splint carrier of the machine, a trough, means for delivering match splints into said trough in such a way that they extend transversely of the trough, means for feeding the match splints through said trough towards said hopper, means for reciprocating said trough endwise, and a vibrating member carried by the trough and arranged adjacent the discharge end thereof for directing the splints towards said hopper.

5. A match making machine, comprising a hopper adapted to hold match splints that are removed from the hopper and inserted in the match splint carrier of the machine, a trough leading to said hopper, means for introducing match splints into said trough, so that they extend crosswise of the same, means for feeding the splints through said trough towards said hopper, a vibrating device arranged in the bottom of the trough adjacent to the discharge end of said trough, and opening in the trough adjacent said vibrating device for permitting improperly positioned splints to escape from the trough.

6. A match making machine, comprising a hopper adapted to hold match splints that are removed from the hopper and inserted in the match splint carrier of the machine, a trough arranged at the upper end of said hopper, means for delivering splints to said trough crosswise of the trough, means for feeding the splints longitudinally through said trough, a pivotally mounted feeding member arranged in the bottom of the trough adjacent the discharge end of the trough for directing the splints towards said hopper, and mechanism for reciprocating

ing said trough and rocking said feed member.

7. A match making machine, comprising a hopper adapted to hold match splints that are removed from the hopper and inserted in the match splint carrier of the machine, a trough arranged at the upper end of said hopper, means for delivering match splints into said trough crosswise of the trough, means for feeding the splints longitudinally through said trough, a vibrating feeding member carried by the trough and arranged in a slot in the bottom of the trough adjacent the discharge end of the trough for directing the splints towards said hopper, mechanism for reciprocating said trough and simultaneously rocking said feeding member, openings in the trough at opposite sides of said vibrating feeding member for permitting improperly positioned match splints to escape from the trough, and a suction device for withdrawing improperly positioned splints through said openings.

8. A match making machine, comprising a hopper adapted to hold match splints that are removed from the hopper and inserted in the match splint carrier of the machine, a trough arranged at the upper end of said hopper, means for moving match splints longitudinally of the trough towards said hopper, means for agitating said trough endwise to arrange the splints in parallel relation, a downwardly-inclined, pivotally mounted feeding member arranged in the bottom of the trough adjacent the discharge end thereof, and means for vibrating said feeding member.

9. A match making machine, comprising a hopper adapted to hold match splints that are removed from the hopper and inserted in the match splint carrier of the machine, a horizontally-disposed trough arranged adjacent the upper end of said hopper and provided with a resilient bottom, means for delivering match splints to said trough, and a splint feeding device comprising portions that travel longitudinally through said trough in engagement with the bottom of the trough.

B. G. VAUGHAN.
